G. BOWMAR

INSULATING HEAD FOR PISTONS

Original Filed Aug. 3, 1922

FIG. 1.

FIG. 2. Inventor,

G. BOWMAR.

By *Fetherstonhaugh & Co.*
Atty's.

UNITED STATES PATENT OFFICE.

GERSHON BOWMAR, OF TORONTO, ONTARIO, CANADA.

INSULATING HEAD FOR PISTONS.

Application filed August 3, 1922, Serial No. 579,469. Renewed November 6, 1923.

To all whom it may concern:

Be it known that I, GERSHON BOWMAR, a subject of the King of Great Britain, and a resident of the city of Toronto, in the county 5 of York, in the Province of Ontario, Canada, have invented certain new and useful Improvements in Insulating Heads for Pistons, of which the following is the specification.

10 My invention relates to improvements in insulating heads for pistons and the object of the invention is to devise a piston head in which means are provided to prevent the heat generated by the explosion of gases 15 within the cylinder from passing through the head and carbonizing the oil therearound, in which the head will not be affected by the heat of the surrounding body of metal to render it inoperative and which 20 is so constructed as to render it easily applicable to insertion in a piston already constructed and it consists essentially of the arrangement and construction of parts as hereinafter more particularly explained.

25 Fig. 1 represents a sectional view of my piston head with my insulating means applied thereto.

Fig. 2 is a similar view of a modified construction.

30 In the drawings like characters of reference indicate corresponding parts in each figure.

Referring first to Fig. 1.

1 indicates a piston of which 2 is the head 35 and 3 the side wall. 4 is a disc-like portion which is cut out of the head comprising that part within the side wall 3. The disc portion 4 is so cut out as to leave a slight intervening annular space 5 between the 40 edges of the disc and the opposing portion of the piston head when the parts are inserted one within the other.

6 is a cupped or dished member formed of sheet metal, the side wall of which is of 45 such a thickness as to fit within the intervening space 5. When the cup 6 is inserted in this position the parts are secured together by electric welding or any other suitable means.

Between the bottom face of the disc portion 4 and the bottom wall of the cup 6 is formed an intervening space 7 which is filled with asbestos wool or any other suitable non-conducting material. 9 is a perforation formed in the disc 4 to let out the 55 air as it expands when the device is first heated. This perforation is afterwards sealed by any suitable means.

In Fig. 2 I show a modified form in which the asbestos filling is dispensed with, the 60 cup member 6* being formed deeper than the cup 6 so as to form an air chamber which, in its self, forms a non-conducting barrier at the head of the piston.

It will thus be seen that I have devised 65 a very simple, efficient and compact construction of insulating piston head in which the wrist pin may be located nearer to the head than is permissible in an ordinary construction, for the reason that the wrist pin 70 of my construction will not be affected by the heat passing through the piston head when in close proximity to the head as in the case in an ordinary construction of piston.

75 What I claim as my invention is:

1. In a piston, a head having the central portion located within the side walls of the piston removed to form a separate disc having its exterior edge slightly spaced apart 80 from the body of the piston, and a cupped member having its wall inserted between the disc and the body of the piston so that the parts may be electrically welded together.

85 2. In a piston, a head having the central portion located within the side walls of the piston removed to form a separate disc having its exterior edge slightly spaced apart from the body of the piston, a cupped member having its wall inserted between the disc and the body of the piston so that the parts may be electrically welded together, and a filling of non-conducting material inserted within the cupped member between 90 the inner face of the disc portion of the head and the bottom of the cup.

95 GERSHON BOWMAR.
